UNITED STATES PATENT OFFICE.

FRED W. FAHRENFIELD, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

HINGE.

Application filed April 10, 1922. Serial No. 551,421.

The present invention relates to hinges in general, but is concerned more particularly with hinges which permit the parts hinged together to be readily taken apart; and the 5 principal object is to provide a new and improved hinge of the above character that is simple in construction and is easy to construct and cheap to manufacture.

Another object is the production of a 10 hinge of the type set forth which when properly applied to a box or the like is entirely enclosed when the box is shut and, therefore, is not only protected but also does not detract from the appearance of the box, 15 on account of being out of sight.

Referring now to the accompanying drawings, comprising Figs. 1-5, inclusive, Fig. 1 is a front view of the base of a box which is provided with the improved hinges, the 20 cover being removed; Fig. 2 is a rear view of the removed cover; Fig. 3 is a cross section on line AAA through Figs. 1 and 2 with the cover in place and closed; and Figs. 4 and 5 are perspective views of a portion of 25 the base 2 and cover 3.

The base 2 is a sheet metal stamping with a raised central portion as can be seen in Fig. 3. The slots 6 and 7 cut in the base 2 are adapted to receive the hinge members 4 and 5 which are riveted on the cover 3. The 30 cover 3, which also is made of sheet metal, has a box like shape and is open in the rear. In order to place the cover 3 on the base 2, the former is rotated from its position in Fig. 2 about an axis formed by a line running through the hinge members 4 and 5 until the plane of the cover is approximately at right angles to the plane of the base 2, at which time the hinge members 4 and 5 35 are now brought into alignment with and inserted into the slots 6 and 7 as shown in Fig. 4. The cover is moved downward slightly to cause the projections 17 and 18 of the hinge members 4 and 5 to come behind and below the lower edges of the slots 6 and 7 as shown in Fig. 5 so as to prevent the cover 3 from being pulled away from base 2. The catch 8 is now rotated about its 40 pivot in a counter-clock-wise direction until the projection 19 thereof strikes the raised portion 10 of the base. In this position the catch 8 prevents the hinge 5 from moving up. The cover 3 may now be swung shut, the raised portions 9 and 10 preventing any 45 binding that might otherwise occur. When

the box is shut the end of the locking tongue 12 is in the notch 11 in the base and serves to hold the box shut by its spring action. The supporting post 14, which is most clearly seen in Fig. 3 is screwed into the cover 3 50 and prevents the tongue 12 from springing too close to the cover 3 when the latter is open. The knob 13 is secured to the cover 3 by a bolt and nut as shown in Fig. 3 and serves as a handle for opening and shutting 55 the box.

When the box is opened the cover is stopped, after it has turned about ninety degrees, by the projections 17 and 18 on the 60 hinges 4 and 5 as they come into engagement 65 with the base 2 at the lower edges of the slots 6 and 7.

Upon referring to Fig. 3, it will be noted that the portion of the base 2 which is engaged by the edge of the cover 3 is formed 70 into an arc of a circle over which the similarly formed hinges 5 and 6 glide when the 75 box is being opened or shut. The hinge 4, of course, is identical with hinge 5.

When it is desired to remove the cover 3 80 from the base 2, it is necessary merely to open the box to the fullest extent and then to rotate the catch 8 out of the path of the hinge 5 after which the cover 3 may be 85 easily pushed up and then lifted off.

The various features of the invention, having been described and ascertained thus, will now be pointed out in the appended 90 claims.

What is claimed is:

1. In combination, a door or cover, a base or support, said support having a trough formed therein, a slot in the support beside said trough, and a hinge member secured to the cover in such a position that an edge of 95 the latter fits into said trough and the surface of the former rides over the opposite side of the trough when the former is inserted into said slot, said hinge member being provided with a projecting extension which engages 100 the base at the edge of said slot, the resulting combination forming a hinge joint which allows said cover to rotate back and forth about said edge as an axis.

2. In combination, a base or support having a slot therein, a curved trough in said support beside said slot and parallel thereto, a cylindrical ridge on the opposite side of said support concentric with said trough and having its surface in line with one edge 105 110

of said slot, a cover or door, a hinge member secured to said cover and having a cylindrical end which may be inserted into said slot and the inner surface thereof rotated around said ridge, and an extending projection on said member adapted to prevent the removal of said cover by engaging with said support at the edge of said slot when said cover is opened to its fullest extent.

3. In combination, a base and cover, a hinge joint for connecting the two, consisting of a plurality of tongues on the cover registering with a plurality of slots in the base, each tongue slidable laterally in its slot, means for preventing lateral movement of the tongue, and a lug on each tongue for preventing its removal from the slot without lateral movement of the cover.

4. In combination, a cover, a base, said base having a trough formed therein, a slot in said base beside said trough, a hinge

member secured to the cover, an edge of the cover always fitting into said trough and the surface of the hinge member concentric with and always riding over the opposite side of the trough when the hinge is inserted into said slot.

5. In combination, a cover, a base, said base having a trough formed therein, a slot in said base beside said trough, an edge of said cover resting in said trough, a hinge member attached to said cover and extending through said slot, said hinge member having a portion concentric to said trough, said cover being rotatable, said edge and trough forming a pivot about which the cover rotates said hinge member riding over the opposite side of said trough to hold said pivot members together.

In witness whereof, I hereunto subscribe my name this 7th day of April, A. D., 1922.

FRED W. FAHRENFELD.
